(57) **CLAIM**

The ornamental design of an invertible license plate frame and mounting adapter, as shown and described.

DESCRIPTION

FIG. 1 is a front elevational view of an invertible license plate frame and mounting adapter showing my new design. The frame in FIGS. 1-5 and the mounting adapter in FIGS. 6-10 are shown separately for ease of illustration.

FIG. 2 is a top plan view thereof,

FIG. 3 is a right side elevational view thereof; the left side elevational view being a mirror image thereof,

FIG. 4 is a rear elevational view thereof;

FIG. 5 is a bottom plan view thereof;

FIG. 6 is a front elevational view of the mounting adapter for attaching the license plate frame showing my new design,

FIG. 7 is a top plan view thereof;

FIG. 8 is a left-side elevational view thereof; the right-side elevational view being a mirror image thereof;

FIG. 9 is a rear elevational view thereof;

FIG. 10 is a bottom plan view thereof; and,

FIG. 11 is a perspective view of an inverted license plate frame being attached via the mounting adapter to a license plate mounting platform. The mounting platform is shown in broken lines for illustrative purposes only and forms no part of the claimed design.
